MACHINE FOR CREEASING CURTAINS AND
THE LIKE

Alfred C. Probst, Erie, Pa.

Application October 1, 1938, Serial No. 232,894

8 Claims. (Cl. 270—61)

This invention relates generally to folding and creasing machines and more particularly to machines for folding and creasing curtains and like fabric.

5 All devices of this character made according to the prior art, and with which I am familiar, have no means of creasing and folding a lace curtain or the like. To cause the lace curtain to hang in a proper manner, it is desirable to have 10 the creases lengthwise of the curtain and heretofore this has been done by hand. It is not practical to add heat to curtain because sharply defined creases are not desirable. In plaiting and like machines heretofore constructed, it has been 15 impossible to crease and fold curtains because it was impossible to take the curtain from the machine without ruining the crease. When heat was added in these machines, the appearance of the curtain with sharply defined corrugations 20 was undesirable and the curtain will not hang correctly. In any machine tried, the curtain would be ruffled and it was necessary to crease them by hand. Curtains are now folded so that they leave cross creases when unfolded thereby 25 requiring ironing before they are hung. In all cases, it has heretofore been necessary to fold and crease curtains lengthwise, by hand and it has required considerable time and the work was not entirely satisfactory.

30 It is, accordingly, an object of my invention to provide a machine for folding and creasing or corrugating curtains or like fabric which is simple in construction, cheap in cost, simple in operation, and easy to manufacture.

35 Another object of my invention is to provide a machine for folding and creasing curtains or the like fabric which permits the removal of the curtain or other fabric from the machine without destroying the crease.

40 Another object of my invention is to provide a machine for folding and creasing curtains and the like fabric lengthwise so that the curtains will be disposed for hanging or packing without further work thereon.

45 Another object of my invention is to provide a machine which crease and fold curtains so that they may be hung as they come from the factory, laundry, or curtain work rooms without any repressing whatsoever.

50 Other objects of my invention will become evident from the following detailed description, taken in conjunction with the accompanying drawings, in which—

Fig. 1 is a plan view of my novel machine for folding and creasing curtains and the like.

Fig. 2 is an end view of my novel machine with the initial raised position of the foldable members shown in dotted lines.

Fig. 3 is a view taken on the line 3—3 of Fig. 2.

Fig. 4 is a view taken on the same line as the

view in Fig. 3 showing the foldable member in initial raised position.

Fig. 5 is a side elevational view of my novel machine showing the foldable members in a completely folded position.

Fig. 6 is a side elevational view as in Fig. 6 showing a curtain partially removed from the machine.

Fig. 7 is a fragmentary end view showing the foldable members in a completely foldable position.

Fig. 8 is an enlarged fragmentary view showing the spacing means for the foldable members.

Fig. 9 is a side elevational view in section of the clip for securing the curtain onto my machine, in open position and Fig. 10 shows the clip in closed position.

Referring to the drawings, Figs. 1 and 2 show a frame 1 with side supports 2 having hinged foldable members 3, 4, 5, and 6 disposed thereon. The foldable members 3, 4, 5, and 6 are normally in a horizontal position as shown in Fig. 1 so that a curtain or the like can be laid out flat on the foldable members 3, 4, 5, and 6 so that all of the ruffles can be removed therefrom before the curtain is folded and creased. It will be evident that any number of foldable members may be used without diverting from the spirit of my invention. The foldable members 3, 4, 5, and 6 are initially raised as shown in the dotted lines of Fig. 2 by the pins 8 and cam members 9, the cam members 9 being operated by handles 10 projecting from the side of the frame 1.

Fig. 3 shows the pins 8 and the cam member 9 in an inoperative position with the foldable member 5 in a horizontal position. Fig. 4 shows the same member 5 in a raised position after the pins 8 have been raised by movement of the cam member 9 through manual operation of the handle 10. The foldable members 3, 4, 5, and 6 successively increase in height in a direction opposite to the direction of fold. The pins 8 are off-set in the direction of fold in order that they will be directly under the peaks of the foldable members 3, 4, 5, and 6 when they reach an initially raised position as shown in dotted lines in Fig. 2. It will be evident that the total length of the hinged connected foldable members 3, 4, 5 and 6 is less in a raised position than in a horizontal position thereby requiring an offset of the pins 8. Springs 11 are connected to cam members 9 and to a cross-arm 12 of the frame 1 in order that the cam members 9 may be returned to an inoperative position when the lock members 13 are released from the notches 14 in the cam member 9.

A shaft 15 having pulleys 16 and a crank handle 17 mounted thereon is supported on the frame 1 and connects the furthermost foldable member 6 by suitable cable or the like 18. Upon rotation of the crank handle 17, the cable 18 will be wound

on the pulleys 16 and the foldable members 3, 4, 5, and 6 will be brought to a folded position as shown in Fig. 7, the foldable member 6 coming to a folded position first and the foldable members 5, 4, and 3 in the order named coming to a folded position. By this method of folding, the curtain or other fabric will not become ruffled and perfect creases and folds will result. The shaft 15 with the pulleys 16 and the crank handle 17 may be disposed on the opposite end of the machine and produce the same results where it is desired to remove the curtain or like fabric from the front end of the machine. I have shown a spring 50 in Fig. 7 for retarding the free movement of the pulleys 16 although it will be evident that any means may be utilized to prevent free rotation of the pulleys 16. Recesses 19 are disposed on each end of the foldable members 3, 4, 5, and 6 in order that a folded curtain or like fabric may be grasped by the hand and removed from the machine. A curtain 7 partially removed from the machine is shown in Fig. 6. Fig. 8 shows the foldable members 20 in folded position provided with spacing means 21. It will be evident that any form of spacing means may be provided.

Figs. 9 and 10 show a clamp 22 for securing a curtain or like fabric onto the foldable members 3, 4, 5, and 6 without damaging the curtain or like fabric. The clamp 22 comprises a pivoted member 23 having a leaf spring 24 extending through an aperture 25. When in the position shown in Fig. 9, the spring 24 holds the pivoted member 23 against the fabric in the machine.

In operation, a curtain or the like fabric is placed on the foldable members 3, 4, 5, and 6 when they are in horizontal position as shown in Fig. 1. The curtain or like fabric is then clamped in position by the clamps 22. Each member 3, 4, 5, and 6 is then initially raised independently by the cam members 9 and pins 8 to a position shown in the dotted lines in Fig. 2. It has been found preferable to raise the foldable members 3, 4, 5, and 6 in accordance with their respective heights, with the lowest initially raised foldable member 3 being raised first and then 4, 5, and 6 in the order named. It has been found that with no initial raising of the foldable members 3, 4, 5, and 6, the curtain or other fabric to be folded and creased will not fold uniformly and many cross creases will be formed. This was likewise true when all of the foldable members 3, 4, 5, and 6 were initially raised the same height. It will be apparent that when the foldable members 3, 4, 5, and 6 are initially raised to successively increasing heights in a direction opposite to the direction of fold, the furthermost foldable member 6 will come to a completely folded position first with members 5, 4, and 3 following in the order named. It will be evident that if all of the foldable members 3, 4, 5, and 6 came to a folded position at the same time, the curtain or fabric to be folded would become ruffled.

After the initial raising of the foldable members 3, 4, 5, and 6 to a position shown in dotted lines in Fig. 2, the crank handle 17 is rotated and the foldable members 3, 4, 5, and 6 are brought to a folded position as shown in Fig. 7 through the cable 18. The curtain or fabric is then removed as shown in Fig. 6. The curtain will be creased in a lengthwise direction and may be immediately hung or it may be packed in boxes in such a manner that they may be taken from the boxes and hung without the necessity of ironing them.

It will be apparent that I have provided a machine for creasing and folding curtains or other fabric lengthwise so that they may be packed or hung as they come from the factory, laundry, or curtain rooms.

Various changes may be made in the specific embodiment of the present invention without departing from the spirit of the present invention, or from the scope of the appended claims.

What I claim is:

1. In a machine for folding and creasing fabric, in combination, interconnected foldable members, means for disposing a fabric on said foldable members, means for raising each foldable member initially to a partially folded position, and means for disposing said foldable members in a folded position whereby said fabric may be removed from said foldable members in a folded position.

2. In a machine for folding and creasing fabric, in combination, foldable members, means for disposing fabric on said foldable members, means for raising each foldable member independently to a partially folded position, and means for folding said members whereby said fabric may be removed from said foldable members in a folded position.

3. In a machine for folding and creasing fabric, in combination, interconnected foldable members, means for initially raising said foldable members to positions progressively increasing in height in a direction opposite to the direction of fold, means for disposing a fabric on said foldable members, and means for moving said foldable members to a completely folded position whereby said fabric may be removed from the foldable members in a folded position.

4. In a machine for folding and creasing fabric, in combination, interconnected foldable members, means for disposing a fabric on said foldable members, means for raising each foldable member to a partially folded position, the height of foldable members being higher on those members having the greatest distance to travel to reach a completely folded position, and means for moving said members to a folded position.

5. In a machine for folding and creasing curtains and the like, in combination, interconnected foldable members, means for securely disposing a curtain or the like on said foldable members, means for initially raising said members to a partially folded position, certain of said members being movable to a higher position than others, and means for moving said foldable members to a completely folded position.

6. A machine as set forth in claim 5 wherein spacing means are provided for the foldable members when in a folded position.

7. A machine for folding and creasing curtains and the like, in combination, foldable members, means for securely disposing a curtain or the like on said foldable members, means for independently raising each folding member to predetermined heights, and means for moving said foldable members to a position substantially parallel with each other.

8. A machine as set forth in claim 7 wherein spacing means are provided for the foldable members when they are in a substantially parallel position.
